(57) **CLAIM**

The ornamental design for the hand operated cutting tool, as shown and described.

DESCRIPTION

FIG. 1 is front view of the second embodiment of a hand operated cutting tool of the claimed design.

FIG. 2 is a top view of the second embodiment hand operated cutting tool of the claimed design.

FIG. 3 is a back view second embodiment of the hand operated cutting tool of the claimed design.

FIG. 4 is a right side view of the second embodiment of a hand operated cutting tool of the claimed design.

FIG. 5 is a left side view of the second embodiment of a hand operated cutting tool of the claimed design.

FIG. 6 is a front view of the third embodiment of a hand operated cutting tool of the claimed design.

FIG. 7 is a top view of the third embodiment of a hand operated cutting tool of the claimed design.

FIG. 8 is a back view of the third embodiment of a hand operated cutting tool of the claimed design.

FIG. 9 is a right side view of the third embodiment of a hand operated cutting tool of the claimed design.

FIG. 10 is a left side view of the third embodiment of a hand operated cutting tool of the claimed design; and,

FIG. 11 is a front view of the second embodiment of a hand operated cutting tool of the claimed design.

The broken line showing of the tool is included for the purpose of illustrating portions of the article and forms no part of the claimed design.
